(57) **CLAIM**

The ornamental design for the mobile terminal, as shown and described.

DESCRIPTION

FIG. 1 is a front view of our new design for a mobile terminal.

FIG. 2 is a rear view of our new design for a mobile terminal.

FIG. 3 is a left side view of our new design for a mobile terminal.

FIG. 4 is a right side view of our new design for a mobile terminal.

FIG. 5 is a top view of our new design for a mobile terminal.

FIG. 6 is a bottom view of our new design for a mobile terminal.

FIG. 7 is a perspective view of our new design for a mobile terminal; and,

FIG. 8 is a second perspective view of our new design for a mobile terminal.
